(57) **CLAIM**

The ornamental design for a control device, as shown and described.

DESCRIPTION

FIG. 1 is top front perspective view of a control device showing our new design;

FIG. 2 is a top plan view thereof;

FIG. 3 is a top rear perspective view thereof;

FIG. 4 is a side view thereof; and,

FIG. 5 is a bottom plan view thereof.

The broken lines indicate unclaimed portions and form no part of the claimed design.
